US00D378408S

United States Patent [19]
Pyeatt et al.

[11] **Patent Number:** **Des. 378,408**
[45] **Date of Patent:** ****Mar. 11, 1997**

[54] **CORD AND TUBE ORGANIZER**

[75] Inventors: **Patricia L. Pyeatt**, Fort Worth; **Troy J. Mullens, Jr.**, Richland Hills, both of Tex.

[73] Assignee: **Tecnol Medical Products, Inc.**, Fort Worth, Tex.

[**] Term: **14 Years**

[21] Appl. No.: **39,619**

[22] Filed: **May 31, 1995**

[52] U.S. Cl. **D24/128; D8/356**

[58] Field of Search **D24/128, 127, D6/567; D8/356; 604/180, 179, 177, 178, 174; 128/DIG. 26; 248/68.1, 205.2, 74.4, 316.4, 316.2**

[57] **CLAIM**

The ornamental design for a cord and tube organizer, as shown and described.

DESCRIPTION

FIG. 1 is a perspective view of a cord and tube organizer showing our new design;

FIG. 2 is a right side elevational view of FIG. 1, the left side being a mirror image thereof;

FIG. 3 is a top plan view thereof;

FIG. 4 is a front elevational view of FIG. 1, the rear elevational view being a mirror image thereof;

FIG. 5 is a bottom plan view thereof;

FIG. 6 is a perspective view of a second embodiment of a cord and tube organizer showing our new design;

FIG. 7 is a right side elevational view of FIG. 6, the left side elevational view being a mirror image thereof;

FIG. 8 is a top plan view thereof;

FIG. 9 is a front elevational view of FIG. 6, the rear elevational view being a mirror image thereof;

FIG. 10 is a bottom plan view thereof;

FIG. 11 is a perspective view of a third embodiment of a cord and tube organizer showing our new design;

FIG. 12 is a right side elevational view of FIG. 11, the left side elevational view being a mirror image thereof;

FIG. 13 is a top plan view thereof;

FIG. 14 is a front elevational view of FIG. 11, the rear elevational view being a mirror image thereof; and,

FIG. 15 is a bottom plan view thereof.

The broken line showing of the perforation in the FIGS. 6, 7, 8 and 10 are for illustrative purposes only and forms no part of the claimed design.

1 Claim, 3 Drawing Sheets
